THOMAS BURTON MILLER, OF SEATTLE, WASHINGTON, ASSIGNOR OF ONE-HALF TO SMITH CANNERY MACHINES COMPANY, OF SEATTLE, WASHINGTON, A CORPORATION OF WASHINGTON.

TELEPHONE RECEIVING INSTRUMENT.

1,114,902.

Specification of Letters Patent.

Patented Oct. 27, 1914.

Application filed September 25, 1912. Serial No. 722,167.

To all whom it may concern:

Be it known that I, THOMAS BURTON MILLER, citizen of the United States, residing at Seattle, in the county of King and State of Washington, have invented a certain new and useful Improvement in Telephone Receiving Instruments, of which the following is a specification.

My invention relates to improvements in telephonic receiving instruments, but more particularly it relates to that class of telephone receivers that are employed in wireless telegraph systems for receiving successive combinations of sounds representing the letters of the well known alphabetic codes, the Morse and the Continental; and the object of my improvement is to provide a receiving instrument whose diaphragm shall be actuated to give perceptible sounds in response to minutest variations in the electrical condition of a circuit within which such telephone is included whereby the slightest amount of electrical energy in form of waves or oscillations in such circuit may be perceived.

I attain this object by devices which are illustrated diagrammatically in the accompanying drawing wherein is shown a pole portion of permanent steel magnet 1 to which is attached a soft iron electro-magnet core which comprises a lower end portion 2, a constricted portion 3 and an upper end portion 4, the said upper end portion 4 being provided with a longitudinal slot 5 which serves, in accordance with a well known principle, to obviate the generation of eddy currents. The permanent steel magnet 1 may, if it be desired, be replaced by an electro-magnet that is associated with suitable well known means for maintaining it in a magnetized condition. A helix 6 of insulated magnet wire is disposed to surround the lower end portion 2 of the soft wire iron electro-magnet core while a similar helix 7 surrounds the upper end portion 4 thereof.

As shown in the drawing, the inner terminals of the helices 6 and 7 are both connected to a circuit wire 8 while their outer terminals are both connected with a circuit wire 9 whereby electricity flowing from circuit wire 8 to circuit wire 9 would find passageway through both helices 6 and 7, but in the helix 6 the electricity would flow in one direction around the lower end portion 2 while in the

helix 7 it would flow in the opposite direction around the upper end portion 4 of the soft iron electro-magnet core. The helices 6 and 7 being connected in multiple to the circuit wires 8 and 9 electricity would find a path through wire 8 to the inner terminals 55 of the helices 6 and 7 there to divide and after passing one half through the helix 6 and the other half through the helix 7 the electricity would reunite where the outer terminals of said helices 6 and 7 connect 60 with the circuit wire 9, as shown. The effect of waves of electrical energy flowing in opposite directions through the helices 6 and 7 is obvious and I have found such form of device to give remarkably efficient results 65 with respect to sensitiveness in detecting slight electrical disturbances in a circuit with which it was connected. Of course such arrangement of helices and circuit connections would give no useful results if the 70 magnet core be not constricted as by the constricted portion 3. A diaphragm 10 is supported by suitable well known means 75 (not shown) with its central portion adjacent to the face of the upper end portion 4 80 of the soft iron electro-magnet core, in the usual manner, it being clamped in its position by an ear-piece of well known form, which is indicated diagrammatically by the curved lines 11 in the drawing. By such 85 construction the magnetic lines of force emanating from the upper portion 4 of the electro-magnet core to flow across the space or gap to the diaphragm 10 are so restricted that such diaphragm 10 is magnetized to a 90 degree below the point of saturation and is therefore more susceptible to changes in the number of such magnetic lines of force, but such diaphragm 10 is sufficiently magnetized 95 normally to be attracted toward the face of the upper portion 4 of the electro-magnet core to a point where the attractive force balances the retractile force due to the elastic or resilient quantity of such diaphragm 10, at which point such diaphragm 100 10 is more sensitive to the slightest degree of variation in the amount of magnetic flux between the face of said upper portion 4 of the electro-magnet and the said diaphragm 10.

Manifestly various forms of permanent steel magnets and various forms of electro-magnets may be substituted for the perma-

nent steel magnet 1, indicated in the drawing, and the dimensions of various parts of my invention may be changed without departing from the spirit thereof.

5 What I claim is:

In a receiving telephone, the combination with a diaphragm, of an electro-magnet core that is constricted in a portion of its length, one end of which electro-magnet core is disposed adjacent to the central portion of said diaphragm, magnetic means associated with the other end of said electro-magnet core whereby such electro-magnet core may be supplied with magnetic lines of force of constant polarity, and two helices of magnet wire disposed each to surround a different one of the portions of said electro-magnet core between which portions said electro-

magnet core is constricted, said two helices being electrically connected with each other 20 to adapt them to be connected to a receiving circuit in parallel with each other so that a portion of an electric current flowing in such receiving circuit would flow around one portion of said electro-magnet core in one direction while the other portion of such electric current would flow in an opposite direction around the other portion of said electro-magnet core.

In witness whereof, I, hereunto subscribe 30 my name this seventeenth day of September A. D. 1912.

THOMAS BURTON MILLER.
